CLAIM

I claim the ornamental design for the controller face with tracking sensors, as shown and described.

DESCRIPTION

The single FIGURE is a front view of a two-dimensional controller face with tracking sensors. Four such sensors are provided for context in the corners of the face of the controller but do not otherwise constitute claimed subject matter.

Those portions of the FIGURE illustrated in hashed lines constitute non-claimed subject matter. These portions of the figure do not constitute a part of the claim and are presented solely for context. The broken line showing the controller and tracking sensors are included for the purpose of illustrating environmental structure and forms no part of the claimed design.

The top plan view is non-claimed subject matter;

The bottom plan view is non-claimed subject matter;

The left side view is non-claimed subject matter;

The right side view is non-claimed subject matter;

The rear view is non-claimed subject matter.
